UNITED STATES PATENT OFFICE.

LUTHER L. KNOX, OF AVALON, PENNSYLVANIA.

RENDERING-KETTLE.

1,229,758.

Specification of Letters Patent. Patented June 12, 1917.

Application filed July 6, 1914. Serial No. 849,044.

To all whom it may concern:

Be it known that I, LUTHER L. KNOX, a citizen of the United States, residing at Avalon, in the county of Allegheny and State of Pennsylvania, have invented a new and useful Improvement in Rendering-Kettles, of which the following is a full, clear, and exact description, reference being had to the accompanying drawings, forming part of this specification, in which—

Figure 1 is a plan view of a rendering kettle embodying my invention; and

Fig. 2 is a central vertical section of the same.

My invention has relation to rendering kettles, such as are used in rendering various oils and lards, etc., and is designed to provide a kettle of this character of novel construction and capable of being manufactured from sheet metal at a relatively low cost.

Referring to the accompanying drawings, in which I have shown a kettle embodying my invention, the numeral 2 designates an outer jacket, which consists of a sheet metal cylinder, open at the top and bottom, and secured by riveting or otherwise at its lower end to a supporting base 3, which may be formed by an angle iron bent into annular form. The bottom of the jacket is formed of a dished sheet metal piece 4, which is welded within the lower portion of the cylinder 2. The inner vessel consists of a cylinder 5, also of sheet metal, but preferably of somewhat heavier stock than the outer jacket, and the dished bottom portion 6, spun or otherwise shaped from a metal sheet and welded to the lower edge of the cylindrical portion 5, as indicated at 7. The upper edge of the cylinder is flanged outwardly, and this flange is welded at 8 to the upper edge of the cylinder 2.

The inner and outer members of the kettle are separated from each other by a space or chamber 9, which is designed to receive steam or other suitable medium. Steam may be introduced through a suitable connection 10 and exhausted through another connection 11. 12 designates the discharge for the oil or fat. This is preferably placed at a level sufficiently high to permit the collection of any sediment deposited from the oil at the bottom of the vessel below such outlet. In the construction of the kettle, I preferably first set up the outer jacket 2, riveting it to the base ring 3, and welding in the bottom 4.

The two ends of the inner vessel are welded together and placed in the outer vessel and the welded joint made at 8. The discharge spout or pipe 12 is then inserted or welded in place.

The entire kettle can be readily formed from sheet metal shapes, which are easily made and united, thus enabling the manufacture to be carried out at a relatively low cost, the welding operations being simple ones. The resulting kettle is practically seamless, and is extremely durable and efficient in operation.

I claim:

1. A steam jacketed rendering kettle having inner and outer members, the outer member being formed of a sheet metal cylinder and a sheet metal head, the edge of said head being welded to the inner face of the cylinder to form a smooth joint at the junction of the cylinder and the head, the inner member being formed of a sheet metal cylinder and a sheet metal head of dished form, said head having an annular flange merging into the dished portion of the head, there being a butt-welded joint between the end of the annular flange on the head and the end of the inner cylinder to form a smooth inner surface on the inner member at the junction of the head and cylinder, the upper edge of the cylinder of the inner member having an annular flange supported on and secured to the upper edge of the cylinder of the outer member, substantially as described.

2. A steam jacketed rendering kettle having inner and outer members, the outer member being formed of a sheet metal cylinder and a sheet metal head, the edge of said head being welded to the inner face of the cylinder to form a smooth joint at the junction of the cylinder and the head, the inner member being formed of a sheet metal cylinder and a sheet metal head of dished form, said head having an annular flange merging into the dished portion of the head, there being a butt-welded joint between the end of the annular flange on the head and the end of the inner cylinder to form a smooth inner surface on the inner member at the junction of the head and cylinder, the upper edge of the cylinder of the inner member having an annular flange, the annular flange being flush with the outer face of the cylinder of the outer member and welded to the upper edge of said cylinder to form inner

and outer walls, which are unbroken by projecting flanges, substantially as described.

3. A steam jacketed rendering kettle having inner and outer members, the outer member being formed of a sheet metal cylinder and a dished sheet metal head, the edge of said head being welded to the inner surface of the cylinder above the lower end thereof to form a smooth joint at the junction of the cylinder and head, the cylindrical portion of the outer member extending below the head to form a support for the kettle, there being an annular flange connected to the bottom of the cylinder portion of the outer member to form a foot therefor, the inner member being formed of a sheet metal cylinder and a sheet metal head of dished form, said head having an annular flange

merging into the dished portion of the head, there being a butt-welded joint between the end of the annular flange on the head and the end of the inner cylinder to form a smooth inner surface on the inner member at the junction of the head and cylinder, the upper edge of the cylinder of the inner member having an annular flange supported on and secured to the upper edge of the cylinder of the outer member, substantially as described.

In testimony whereof, I have hereunto set my hand.

LUTHER L. KNOX.
